UNITED STATES PATENT OFFICE.

GEORGE E. WARREN, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

WOODEN SOLE FOR BOOTS AND SHOES AND METHOD OF MAKING SAME.

1,355,436.

Specification of Letters Patent. Patented Oct. 12, 1920.

Application filed October 10, 1918. Serial No. 257,589.

To all whom it may concern:

Be it known that I, GEORGE E. WARREN, a citizen of the United States, residing at Swampscott, in the county of Essex and State of Massachusetts, have invented certain Improvements in Wooden Soles for Boots and Shoes and Methods of Making Same, of which the following description, in connection with the accompanying drawings, is a specification, like reference characters on the drawings indicating like parts in the several figures.

The present invention relates to improvements in the manufacture of shoes of the type in which the bottom or tread portion of the shoe is made of wood. The invention is herein shown by way of illustration in its application to a wooden sole which may be utilized in place of a leather outsole to provide a bottom for a shoe.

According to the present methods of making wooden soles for shoes a wooden block of the required size is cut away with suitable wood working tools until the block has been reduced to the final shape and contour desired for the sole. In shaping these soles so that they will provide the required "spring" for the forepart of the sole and for the shank portion to enable a heel to be attached to the shoe the annual rings or grain of the wood instead of extending continuously from the toe to the heel of the sole is severed crosswise where the sole is curved longitudinally. As a result of this soles are very apt to break and split when subjected to the severe usage for which a shoe having a sole of this kind is intended and especially when a strain is exerted across the grain of the sole. Moreover, the present methods of producing wooden sole shoes involve the use of a grade of wood which is substantially free from knots and other defects and a considerable part of the wood is wasted in producing the soles.

It is an object of the present invention to improve the manufacture of wooden soles for shoes whereby they may be made more economically than the prior methods permit and produce a stronger and more serviceable sole.

With this object in mind the invention in one important aspect provides for the production of a wooden sole by a procedure which consists in first selecting a substan-

tially flat sole-shaped blank of wood having 55 its annual rings extending substantially continuously from end to end, then treating the blank to render it susceptible to a molding pressure, subjecting the blank to a molding pressure adapted to impart the desired conformation to the blank and produce substantially the longitudinal and transverse curvatures of the bottom of the shoe, including the spring required for the sole to receive the heel, and causing the blank to become set 65 in the said conformation and in the form of a molded sole. In practice it is preferable to use a block having a substantially straight grain parallel to the opposite sides of the block to enable the block better to withstand 70 the sole molding strain which would ordinarily be greater than any to which the completed sole is subjected when in use and also to provide for a uniform wear on the tread surface of the sole. Conveniently the block 75 is rendered moldable by subjecting it to the action of moist heat after which it is placed between two metallic forming plates which have acting surfaces corresponding to the contour of the bottom of a last and the sole 80 block and then subjected to pressure for a sufficient length of time to "set" the block to the contour of the plates. The molding of the sole blank, in addition to imparting to it the desired contour, acts to compress and 85 condense the fibers of the wood whereby it is rendered more durable and wear resisting. By this process of manufacture a considerable saving is effected in the amount of wood necessary to make a sole and grades of wood 90 not adaptable to prior methods can be used to advantage. It will be further noted that a sole produced in this manner is more serviceable and less liable to break or split than the wooden soles heretofore produced by removing the wood to form the different curvatures of the sole since the annual rings 95 of the wood extend continuously from toe to heel whereby the maximum strength of the wood is preserved.

The above and other objects of the invention will be set forth in connection with the accompanying drawings and the invention will then be defined under the appended claims.

Figure 1 is a perspective view, partly in longitudinal section, showing the sole blank such as is used in the production of a wooden

100

105

sole in accordance with the preferred practice of the invention;

Fig. 2 is a side elevation illustrating the step of imparting the desired conformation 5 to a sole blank;

Fig. 3 is a side elevation of a shoe showing the incorporation of the sole in the shoe, portions of the shoe being shown in section to illustrate one form of attachment of the 10 sole;

Fig. 4 is a transverse section through the shank portion of the shoe illustrated in Fig. 3; and

Fig. 5 is a transverse section through the 15 forepart of the shoe illustrated in Fig. 3.

In the use of a preferred embodiment of the invention a sole-shaped blank 2 of wood of suitable thickness to constitute the outer sole of a shoe is first selected. It is important that the annual rings or laminæ 20 of the wood indicated at 4 extend substantially continuously from the opposite ends of the blank and also run substantially parallel to the opposite sides of the blank in order that the maximum strength of the wood blank be preserved so as to withstand the subsequent molding operation to which the blank is subjected and provide the greatest wear for the finished sole.

30 In the preparation of this blank for it to constitute a sole for a shoe it is necessary for the blank to have a shape corresponding to the longitudinal and transverse curvatures of the shoe bottom to which the 35 sole is to be applied, including the spring of the sole at the toe and the arched shank portion to provide support for the arch of the foot. Accordingly the blank is subjected to the application of moist heat or 40 steam to render the wood conformable and moldable to a predetermined contour. Conveniently the wood blank is also treated with a waterproofing solution, for example oil or creosote to cause the sole to reject 45 water whereby the comfort and the serviceability of the finished shoe is increased and the molded conformation of the sole is retained. After the sole blank 2 has been rendered moldable it is placed between two 50 metal forms 6 and 8 the acting surfaces of which are so contoured as to impart the desired longitudinal and transverse curvatures to the sole blank for its subsequent attachment to the shoe. Through the forepart portion A of the sole only a slight 55 transverse curvature is necessary, as shown in Fig. 2, while through the shank portion B a more pronounced transverse curvature is desirable in order for the sole to support 60 the arched portion of the foot, as shown in Fig. 4. As herein illustrated, the sole is not provided with an integral heel member but has its heel seat portion C conformed to 65 provide a suitable seat to receive a separate heel member of wood or other wear-resist-

ing material and the longitudinal curvature of the sole in the shank is consistent with the height of the heel to be used. Any suitable compressing apparatus may be used for applying a direct pressure to the sole 70 blank located between the molds 6, 8 to cause the molds to impart the desired conformation to the sole blank. The pressure to which the sole blank is subjected, in addition to shaping the sole, acts to condense 75 and compact the fibers of the wood and thus make the sole more durable and wear-resisting. By reason of the grain of the wood extending practically continuously from end to end of the blank and more or less parallel 80 to the opposite sides of the blank, a considerable pressure can be applied to the blank without liability of breaking it either crosswise or longitudinally of the sole as would be the case were the grain to run at 85 an angle to the general plane of the sole. Moreover, a sole blank of greater thickness can be more readily molded to the desired shape without danger of breaking. The sole is then caused permanently to assume the 90 shape imparted to it by the molds 6, 8 either by leaving it a sufficient length of time to dry out and become set while under the pressure of the molds or by applying artificial heat to the sole.

95 The illustrated sole is herein intended for use in place of a leather outsole in the manufacture of a metallic fastened shoe, for example a standard screwed shoe such as illustrated in Fig. 3. A shoe of this type 100 consists of an upper 12 the marginal portion of which is lasted over on to the upper surface of an insole 14 of leather or other suitable material. The sole 2 is then applied to the shoe bottom and attached by headless 105 screws 16 inserted through the margins of the sole, shoe upper and insole. Subsequently a heel 18 is attached to the shoe in any well-known manner. In using the wooden sole of the invention the sole is 110 applied to the shoe bottom in place of the leather sole and attached to the shoe in substantially the same manner.

115 It will be noted that the wooden sole above described can be made more economically and uniformly than the soles made by the prior methods of removing portions of the wood until reduced to the desired shape inasmuch as it is not necessary to use a comparatively larger piece of wood in the first 120 instance than that of the finished product, thus avoiding a considerable waste in wood. Moreover, with prior methods, it was necessary to select a piece of wood having a uniform and close grain. In fact, a large number of soles unsuitable for use result from defects in the piece of wood selected which could not be determined until after the sole was in process of manufacture. By shaping in the manner above described a wood 130

blank in which the grain of the wood extends continuously from end to end and parallel to the opposite sides the maximum strength of the wood is preserved so that
5 the sole is not apt to split when subjected to strain crosswise of the grain as is very liable to happen with a cut out wooden sole. Also, because the fibers of the wood are compacted by the pressure of the sole shaping
10 operation a more wear-resisting tread member is obtained.

The shoe resulting from the invention is exceedingly durable and wear resisting and well adapted to the severe usage for which
15 a heavy soled shoe is intended. Moreover, a shoe having a wooden sole constructed in accordance with the invention may be made more comfortable and lighter in weight than the wooden soled shoes heretofore made, due
20 to a large extent to the fact that those methods of manufacturing wooden soles were only adaptable to the production of a very thick and clumsy sole.

Having thus described my invention, what
25 I claim as new and desire to secure by Letters Patent of the United States is:

1. As an improved article of manufacture, a wooden outsole for shoes consisting of a single sole-shaped wooden block having its
30 grain extending substantially continuously

to opposite ends of the block and parallel to opposite sides of the block and molded to conform to the longitudinal curvature of the bottom of a shoe, including the spring required for the sole to accommodate a heel 35 for the shoe and for the toe portion of the outsole.

2. That improvement in methods of making wooden outsoles for shoes which consists in selecting a substantially flat sole-shaped blank of wood having its annual rings extending substantially continuously to opposite ends, subjecting the blank to the action of moist heat to render it moldable into predetermined shape, subjecting the 45 blank to a molding pressure adapted to impart the longitudinal and transverse curvatures to the blank corresponding to those of the bottom of a shoe including the spring required for the sole to accommodate a heel 50 for the shoe and clearance for the sole at its toe portion, allowing the blank to dry out and permanently assume the shape imparted to it while under molding pressure, and thereafter removing the sole from the mold- 55 ing pressure.

In testimony whereof I have signed my name to this specification.

GEORGE E. WARREN.
